UNITED STATES PATENT OFFICE

2,369,831

TREATMENT OF OIL PRODUCING SANDS

Philip H. Jones, Redondo Beach, and Marcellus T. Flaxman, Inglewood, Calif., assignors to Union Oil Company of California, Los Angeles, Calif., a corporation of California

No Drawing. Original application April 25, 1939, Serial No. 269,910, now Patent No. 2,342,106, dated February 22, 1944. Divided and this application April 13, 1943, Serial No. 482,940

2 Claims. (Cl. 252—8.55)

This invention relates to the production of oil from oil-producing formations and particularly to a method of increasing the effective permeability of oil-containing formations immediately surrounding a well bore hole and is a division of our co-pending application Serial No. 269,910, filed April 25, 1939, now Patent No. 2,342,106, granted Feb. 22, 1944.

In the drilling of oil and gas wells, particularly by rotary tool methods, it is conventional to employ a drilling fluid to aid the drilling operations. The drilling fluid, generally an aqueous suspension of solid matter, such as clay, bentonite or other similar material or even plain water, is circulated down through the drill stem around the tool or drill bit employed for the drilling operation and rises between the drill stem and the wall of the bore hole to the surface of the well. One purpose of the use of the drilling fluid is to carry to the surface of the bore hole the cuttings made by the drill bit. However, one of the most important functions of the drilling fluid is, by its weight and pressure, to prevent the well from "blowing in" prematurely. The prevention of the "blowing in" or the entrance into the bore hole of the high pressure fluids contained in the penetrated formations requires that the drilling fluid be at a relatively higher pressure than that contained in the penetrated formations. In order to insure that the pressure of the drilling fluid shall be sufficiently great, it is conventional to add to the drilling fluid such weighting materials as barytes, hematite or finely divided iron when the clay content of the said fluid is not in itself sufficient. The producing formation being pervious and the drilling fluid thus being under a relatively high pressure head at the level in the bore hole adjacent the producing formation, a penetration and substantial infiltration of the aqueous phase of the drilling fluid to the formation generally occurs. Connate water may also be present in the producing formation together with the oil and gas therein prior to the drilling operations.

Whatever the origin of the water in the producing zone may be, it is found that its presence therein seriously impairs the subsequent productivity of the well, particularly in low pressure zones. Since it apparently has a higher adhesive tension than oil for the surface of the sand particles in the productive zone, the water apparently partially displaces the oil film from the sand grains and capillaries. In any event, whatever is the actual physical state of the water in

the producing formation, its presence in the producing formation actually greatly reduces the effective porosity and permeability of such formations immediately surrounding the bore hole with the result that the rate at which oil or gas or mixtures thereof can subsequently pass through such formation in flowing to the well is greatly reduced.

Therefore, it is apparent that if the water in the oil or gas-producing formations could be removed from these structures in the immediate vicinity of the well bore hole, the effective permeability of the formation and the production rates from such a well could be appreciably increased.

It is accordingly an object of this invention to provide a treatment for removing water from the oil or gas-producing formations immediately surrounding the well bore hole and thus to increase the effective permeability of such formations and the productivity of the well.

It has been discovered that the removal of water from the producing sands can be effectively accomplished by subjecting them to the washing action of so-called soluble oils which are capable of lowering the surface tension forces holding the water in the sands and of dissolving or emulsifying the water.

The wash oils which have been found suitable for removing water from producing formations are in general the so-called soluble oils having the ability to disperse spontaneously in water and under some conditions the property of apparently dissolving both the oil without visual occurrence of two phases. It is probable that such oils form emulsions with the water which in some cases where the refractive indices of the oil and water phases are substantially equal which cannot be distinguished from a homogeneous solution by ordinary visual inspection. However, when an excess of water is taken up with the soluble oil, it finally assumes the appearance of an emulsion but the dispersed particles are found to be exceedingly small and readily able to pass through the small capillaries, such as occur in permeable oil-producing formations.

Soluble oils which have been found to be suitable are in general the sulfonated mineral and vegetable oils and the water-soluble salts thereof. For example, sulfonated castor oil and sulfonated olive oil have been effective. A sulfonated mineral oil, such as that produced as a by-product by the heavy acid treatment of a petroleum fraction to give what is known as a white oil, and the sodium or potassium salts of such sulfonated oil has been found to be effective.

A compounded soluble oil containing the before mentioned sulfonated mineral oil which has been found to be particularly suitable for treating wells to increase the effective permeability of the surrounding oil-producing formation comprises a mixture of the following materials:

	Per cent by weight
A sulfonated petroleum fraction, such as PB emulsifier manufactured by Sonnenborn and Sons (sodium and/or potassium salt of sulfonated petroleum fraction) --	16.1
Potassium corn oil soap --	8.1
Diethylene glycol --	3.2
Methyl carbitol --	3.2
Rosin --	3.2
Water --	4.8
Light naphthenic lubricating oil fraction (approximately 100 sec. S. U. at 100° F.) --	61.4
Total --	100.0

Other soluble oils made with other emulsifiers which are useful as wash oils are as follows:

	Per cent
Potassium naphthenate --	15.0
A high naphthenic lubricating oil fraction having a viscosity of approximately 100 sec. S. U. at 100° F. --	85.0
Total --	100.0

Aerosol (an ester of a sulfonated bicarboxylic acid produced by the method disclosed in U. S. Patent No. 2,028,091) --	1.0
A light naphthenic lubricating oil fraction, such as kerosene or distillates having a viscosity of approximately 45 sec. S. U. at 100° F. --	99.0
Total --	100.0

	Per cent
Sulfonated oleic acid or sulfonated castor oil --	20.0
Oleic acid --	5.0
A light naphthenic mineral oil fraction having a viscosity of approximately 45 sec. S. U. at 100° F. --	75.0
Total --	100.0

	Pounds
Diglycol laurate --	10
Ethyl alcohol --	2
Naphthenic petroleum fraction having a viscosity of approximately 45 sec. S. U. at 100° F. --	45
Total --	57

Other materials which in themselves have been found suitable for treating the productive sands are sulfonated fatty oils and acids and water soluble salts thereof, sulfonated mineral oil and water soluble salts thereof. Examples of sulfonated fatty oils are sulfonated castor and sulfonated olive oil. An example of a sulfonated mineral oil is that produced as a sulfonated by-product of "white oil" manufacture, resulting from a heavy sulfuric acid treatment of a paraffin petroleum fraction which may have a viscosity ranging from approximately 50 sec. to 400 sec. Saybolt Universal at 100° F.

In practice, the treatment of penetrated oil or gas productive sands with the soluble wash oil is preferably made after the drilling of the

well has been completed although in some cases the material may be added to the drilling fluid during the drilling operation through the oil-producing sands. When the treatment is performed on a completed well ready for production, the soluble oil is introduced into the well in a body and allowed to flow by gravity to the penetrated oil sands or to be circulated to the said sands with the drilling fluid under pressure.

Under the latter method it is desirable to employ slideable plugs or division dams at the interface between the introduced wash oil and the mud which may pass down through the casing upon circulation of the said drilling mud in a manner similar to that employed in the conventional method of cementing wells. It may be desirable to impress additional gas or oil fluid pressure upon the liquid in the well to force the wash oil into the producing formation to be treated. The wash oil having been circulated to the producing formation, the pressure on the fluid contents of the well containing the wash oil may then be varied to cause the oil to alternately penetrate the formation and to return from the formation to the well bore thereby more effectively scrubbing the sands surrounding the well bore hole and thereby at the same time carrying the dissolved water with the returning wash oil to the said well bore hole from which it may subsequently be removed. The balance of the soluble wash oil remaining in the treated formation surrounding the bore hole together with its content of dissolved water from the said formation is subsequently removed by the flow of the oil upon production of the well.

The quantity of liquid to be employed for the treating operation will, of course, vary with each well, depending primarily on the diameter of the bore hole at the bottom of the well and on the thickness of penetration of the oil-producing sands. In general, however, a sufficient amount of the wash liquid is introduced into the well to force the liquid approximately four or five feet into the surrounding formation by the hydrostatic head of the combined fluid in the bore hole. As stated hereinabove, a desirable method of effecting the penetration of the wash oil into the producing formation the required distance, is to introduce the required amount of the wash material into the well and then place it under a superimposed pressure for a sufficient time to cause the material to penetrate into the formation and dissolve the water contained in it. The necessary pressure to force the material into the formation may be supplied by forcing a gas, such as air or fixed hydrocarbon, into the well until a sufficient pressure is provided therein. After the material has been maintained at the producing zone under the superimposed gas pressure for a sufficient period of time, say twelve to twenty-four hours, the pressure may be released to atmospheric and the liquids in the well pumped or bailed out. If desired, the application of the pressure on the formation in this manner may be carried out intermittently, that is, the material introduced into the well may be maintained under pressure for a shorter period of time, say for one hour, and then the pressure released for a corresponding period of time to allow the dissolved material or emulsified water to flow back into the well. The pressure is then reapplied to the formation for another period of time and then again released and so on until the proper treatment of the producing formation has been accomplished.

In some cases it may be necessary to repeat the above operations one or more times using fresh liquid for each operation in order to obtain the desired treatment because the liquid employed in any one operation may be contaminated with a sufficient amount of connate water or other dissolved substances before it has been able to penetrate a sufficient distance in the oil-producing sands to accomplish the desired reduction and effective permeability thereof.

While the application of our invention is particularly suited to low producing wells in low pressure formations which have been in operation for a considerable period of time, the invention is equally well adapted to the treatment of new wells. In the treatment of new wells, however, which are initially large producers of oil or gas, it may be preferable to first bring the well into production and to allow the well to continue to produce until the oil production rate is materially reduced before the treatment to remove the con-

nate and other water in the formation is made.

The above description of our invention is not to be taken as limiting since many variations may be made by those skilled in the art within the scope of the following claims:

We claim:

1. A method of increasing the production of an oil or gas well comprising introducing a mixture of an alkali metal naphthenate and a naphthenic mineral oil fraction into the well, forcing said mixture into the interstices of the formation to contact water adsorbed therein, subsequently withdrawing said mixture together with said water from the formation and subsequently producing the well.
- 10 2. A method according to claim 1 in which the naphthenic mineral oil fraction is a lubricating oil having a viscosity of approximately 100 seconds Saybolt Universal at 100° F.

20
